POWER APPLYING UNIT

Augustus F. Klasing, St. Petersburg, Fla.

Application November 12, 1936, Serial No. 110,518

3 Claims. (Cl. 74—505)

This invention relates to power applying units possessing special utility as operating means for the hand brakes of railway cars, and has particular reference to improvements in power applying units of the general type described and claimed in Klasing Patent No. 1,927,237, dated September 19, 1933.

Generally stated, the object of the present invention is to provide improvements in power applying units of the general type disclosed in the aforementioned Klasing patent, to the end of reducing the production cost of such units while increasing their durability and reliability and rendering them generally more satisfactory in service.

More particularly stated, certain objects of the present invention are to provide a construction whereby the parts of the unit may be assembled and disassembled with facility and whereby the parts are held in a simple, effective manner against accidental disassembly; to provide for adequate lubrication of all working parts of the unit over long periods of time without manual attention; and to provide in an improved way for ready interchangeability between different hand operated elements of the unit such, for example, as a hand wheel and a lever.

With the foregoing other objects in view, which will become more fully apparent, as the nature of the invention is better understood, the same consists in the novel features of construction, combination and arrangement of parts as will be hereinafter more fully described, illustrated in the accompanying drawings and defined in the appended claims.

In the drawings, wherein like characters of reference denote corresponding parts in the different views:

Figure 1 is a front elevation of a power applying unit constructed in accordance with a practical embodiment of the invention, the lower half of the hand wheel operating element of said unit being broken away to show the underlying portions of the unit.

Figure 2 is a side elevation of the unit shown in Fig. 1.

Figure 3 is an enlarged central, vertical, transverse section through the unit.

Figure 4 is a section on the line 4—4 of Fig. 3.

Figure 5 is a fragmentary front elevation of the portion of the housing of the unit in which a pawl for cooperation with a gear of the unit is housed.

Figure 6 is a detail perspective view of the supporting shaft for the pawl referred to.

Figure 7 is a view partly in side elevation and partly in section of the pinion shaft of the unit.

Figure 8 is an enlarged sectional view taken on the line 8—8 of Fig. 2 showing the pawl in posi-

tion to hold the gear with which it cooperates against rotation in one direction.

Figure 9 is a view similar to Fig. 8 showing the pawl disengaged from the gear with which it cooperates.

Figure 10 is a fragmentary side elevation illustrating a lever operating element for the unit.

Figure 11 is a section on the line 11—11 of Fig. 10; and

Figure 12 is a section on the line 12—12 of Fig. 10.

Referring to the drawings in detail, it will be observed that the present power applying unit includes, as usual, a supporting means in the form of a housing, designated generally as A, which is closed at its top, partly closed at its sides, open at its bottom, closed at its front and rear by walls 10 and 11, respectively, and provided with suitable formations 12 adapting it to be bolted or otherwise suitably fastened to a car body or other structure on which the unit is to be used.

At points suitably spaced downwardly from the top of the housing A the front and the rear walls 10 and 11 of said housing are provided with aligned openings 13 and 14, respectively, in which are supported the outer and the inner end portions, respectively, of a drum shaft 15 having rotatably mounted thereon, between said walls 10 and 11, a drum 16 and a spur gear 17, which latter is integral or otherwise rigid with said drum.

In mounting the drum 16 and the spur gear 17 on the shaft 15, the drum and the spur gear first are positioned between the housing walls 10 and 11 with their shaft receiving openings in alignment with the openings 13 and 14 in said housing walls. The shaft 15 then is inserted from the front of the housing, first through the opening 13, then through the openings in the drum and the spur gear and finally into the opening 14 until a head 18 of square or other suitable polygonal shape on the outer end of the shaft engages in a square or other suitable polygonally shaped recess 19 in the outer housing wall 10. A cotter pin 20 or any suitable equivalent thereof then is passed through an opening in a lug 21 at one side of the recess 19 and is secured in overlying relationship to the outer face of the shaft head 18. The shaft 15 thus is secured against accidental displacement from the housing A and also against rotation, due to the cooperation between its polygonal head 18 and the walls at the sides of the recess 19.

The drum 16 is designed to have wound thereon a chain or other suitable flexible pulling or power transmission element 22, which is understood to be connected with a brake or other device to be operated, and in order to guide the winding of said element onto and off of said drum, the latter preferably is provided with a 60

spiral guide rib 23. The upper end of the flexible element may be secured to the drum 16 or may be fastened to a lug or other suitable formation 24 on the spur gear 17 as shown. For rotating the spur gear 17, thereby to rotate the drum 16 to wind the flexible element 22 thereon, there is provided a pinion 25 which is in mesh with the spur gear 17 and which is carried by a shaft 26 journaled in front and rear bearings 27 and 28 mounted in bearing accommodating openings 29 and 30, respectively, in top portions of the front and the rear walls 10 and 11, respectively, of the housing A.

The pinion 25 preferably, but not necessarily, 15 is integral with the shaft 26 and in any event is rigid with said shaft, and preferably is provided with shrouds 31 extending preferably the full depth of the teeth thereof, whereby its teeth are strengthened and whereby, due to said 20 shrouds overlying the ends of the teeth of the spur gear 17, its disengagement from said spur gear by endwise movement of the shaft 26 is prevented so long as the spur gear 17 is operatively mounted in the housing A. It follows, therefore, 25 that in order to assemble the unit the shaft 26 must be placed in the housing prior to mounting the spur gear 17 and the drum 16 therein, and that in order to disassemble the unit the spur gear 17 and the drum 16 must be removed prior 30 to removal of the shaft 26.

The rear bearing 28, preferably in the form 35 of a bronze bushing, is removably, replaceably mounted in the opening 30 in the rear wall 11 of the housing A and has journaled therein the rear end portion of the shaft 26 which extends rearwardly beyond the pinion 25. Either said bearing, or the portion of the shaft 26 which is journaled therein, or both said bearing and said shaft portion, preferably is or are, provided with 40 one or more lubricant containing and distributing grooves or channels 32 which preferably opens, or open, through the rear end of said bearing or said shaft, or through the rear ends of both said bushing and said shaft, as the case may be, into 45 a lubricant containing pocket 33 formed as part of the housing wall 11. Accordingly, by packing the pocket 33 with a suitable grease or other lubricant when the unit is assembled, the bearing 28 and the portion of the shaft 26 which is journaled therein are assured of an ample supply of lubricant over a long period of time without manual attention.

As in the case of the rear bearing 28, the front bearing 27 for the shaft 26 also preferably is in 55 the form of a bronze bushing, preferably of one-piece construction, and is removably, replaceably mounted in the opening 29 in the front wall 10 of the housing A, being retained securely and positively within said opening by a bolt 34 extending 60 transversely through the top portion of said housing and through a transverse groove 35 in the top portion of said bearing. Inwardly of the bearing 27 the shaft 26 is provided with a flange 36 which cooperates with the inner side 65 of said bearing to prevent outward movement of said shaft as long as said bearing 27 is held operatively mounted within the opening 29. However, when the bearing 27 is removed, as 70 permitted by first removing the bolt 34, and assuming previous removal of the spur gear 17, the shaft 26 with its pinion 25 is readily removable through the opening 29 due to said opening being, as shown, of greater diameter than the pinion 25. Conversely, in assembling the unit, the bearing 27 is inserted over the shaft 26 into the open-

ing 29 after the inner end portion of said shaft and the pinion 25 have been passed through said opening 29 as will, of course, be understood.

Either the bearing 27, or the portion of the shaft 26 which is journaled therein, or both said bearing and said shaft portion, is, or are, provided with one or more grooves or channels 37 closed at its, or their, ends and disposed within the planes of the ends of the bearing, to be packed with lubricant when the unit is assembled, 10 to assure a lasting supply of lubricant for said bearing 27 and the said portion of the shaft 26 which is journaled therein.

Outward of its portion which is journaled in the bearing 27, the shaft 26 is tapered or otherwise suitably formed, as indicated at 26', to have removably mounted thereon a hand wheel 38, a nut 39 being threaded on the outer end portion of said shaft against the hub of said hand wheel, or any other suitable means being provided, to 20 fasten said hand wheel on said shaft.

As is customary in devices of this general character means are provided to hold the spur gear 17 against accidental retrograde movement, the means shown comprising a pawl 40 located in the 25 housing A for cooperation with the spur gear 17, said pawl being non-rotatably mounted on a shaft 41 journaled in openings 42 and 43 in the front and the rear walls of the housing A. The shaft 41 is provided with a key 44 which, upon 30 assembling said shaft with the pawl 40, slides through a keyway 45 in the front housing wall 10 opening into the front bearing opening 42 and enters a keyway 46 in the pawl 40.

The forward end of the shaft 41 is equipped 35 with a head 47 located outside of the housing and shaped as shown to present stop portions 48 and 49. A weight 50 is journaled on the shaft 41 between the front face of the housing and the head 47 and is provided with a projection 51 presenting oppositely facing shoulders 52 and 53 which cooperate with the shoulders 48 and 49, respectively. When the weight 50 is in the position shown in Figs. 4 and 8, the pawl 40 is urged by the weight into engagement with the teeth of 45 the gear 17. On the other hand, when said weight is thrown to the position shown by dotted lines in Fig. 9 it moves the pawl 40 out of engagement with the teeth of the spur gear 17, thereby to release the latter.

The positions of the keyways 45 and 46 relative to the front bearing opening 42 and the pawl 40, respectively, are such that the pawl cannot be rotated to a position to aline its keyway with the keyway 45 as long as the spur gear 17 is operatively disposed within the housing A. Therefore, the pawl 40 must be mounted on its shaft 41 prior to mounting the spur gear 17 in the housing A, which means, of course, that when said spur gear subsequently is mounted 55 in said housing, the pawl shaft cannot be rotated to a position to aline its key with the keyway 45 and that said pawl shaft therefore 60 cannot be removed from its bearing openings without first removing the spur gear 17.

A pocket 54 similar to the pocket 33 may be, 65 and preferably is, provided to supply lubricant to the bearing for the inner end of the pawl shaft 41.

In accordance with the present invention pro- 70 vision is made for substitution of an operating element in the form of a lever and a pawl and ratchet mechanism in lieu of the hand wheel 38, so that either the hand wheel or said lever and pawl and ratchet mechanism may be used 75

according to preference or desirability in any particular case.

The lever and pawl and ratchet mechanism referred to comprises a shaft 55 which is, or may be, of the same construction as the shaft 26, except that its outer end, instead of being tapered or otherwise formed to have a hand wheel mounted thereon, is integrally or otherwise rigidly provided with ratchet teeth 56.

10 A combined pawl and lever mechanism for cooperation with the ratchet teeth 56 to rotate the shaft 55 comprises a casing 57 rotatably mounted on the shaft 55 and a lever 58 pivoted to said casing as indicated at 59 and having formed integrally therewith a pawl 60 for direct coaction with said ratchet teeth. The casing 57 comprises a hood section 61 and a plate section 62 secured together in enclosing relationship to the ratchet teeth 56 by one or more bolts or rivets 63, the pivotal support for the lever 58 being comprised by alined bosses 61', 62' on said hood and plate sections, respectively, through which bosses one of the bolts or rivets 63 preferably extends. The plate section 62 is formed 15 with an opening 64 of a shape preferably corresponding to the shape of the ratchet teeth 56 to permit said section 62 to be moved inwardly along the shaft 55 to a position at the inner side of the ratchet teeth 56 prior to assembly 20 of the sections 61, 62. Moreover, said plate section 62 is suitably recessed to accommodate a two-part bushing 65 to provide a bearing for the lever 58 on the shaft 55 at the inner side of the ratchet teeth 56, the bushing halves preferably having formations to fit the opening 64 25 in the plate section 62 whereby the bushing is held against rotation relative to said plate section. The plate section 62 first is engaged over the shaft 55, the bushing 65 then is assembled around the shaft and engaged with the 30 plate section 62, and finally the hood section 61, which is provided with a bearing opening 66 to accommodate the outer end portion of the shaft 55, is assembled with the plate section 62, being fastened thereto by the bolts or rivets 63. 35 The lever 58 extends through an opening 67 in the side of the hood section 61 and said opening is of sufficient length to permit said lever to be swung on its pivot 59 to engage and disengage the pawl 60 with and from the ratchet teeth 56.

The end wall of the hood section 61 preferably is provided with a grease pocket 68 which opens into the bearing opening 66 and also into a grease passageway 69 in the shaft 55, which passageway has branches 70 leading to the journal opening in the bushing 65. The pocket 68 is packed with grease when the mechanism is assembled to assure a lasting supply of lubricant 45 for the journal connections between the shaft 55 and the casing 57.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

70 I claim:—

1. A power applying unit of the character described comprising a support having spaced apart front and rear walls and adapted to be fastened

with its rear wall against a wall of a car or the like on which the unit is to be mounted for use, said walls having alined shaft receiving openings, a drum shaft mounted in said openings and removable from said openings through the opening in the front wall, a drum and a gear rigid therewith mounted on said shaft between said walls, means for rotating said gear and drum, a flexible pulling element to be wound onto said drum by rotation thereof, a head formation on the outer end of said shaft having a flat side surface, a flat surface on the front wall of the support for cooperation with the flat side surface of said head to hold said shaft against rotation, and a securing element removably engaged with a portion of said front wall and overlying the outer end of the head formation of said shaft to hold the latter against removal from the openings in said front and rear walls.

2. In a power applying unit of the character described, a support having spaced front and rear walls, a drum and gear unit removably mounted between said walls, a bearing carried by said rear wall and a bearing accommodating opening in said front wall, a bearing removably mounted in said opening, a power shaft extending between said walls and journaled in said bearings, a pinion of larger diameter than said power shaft rigid with the latter and in mesh with said gear, said opening being of a diameter to permit removal of said power shaft and pinion therethrough as a unit when said removable bearing is removed, said removable bearing being in the form of a one-piece bushing having a groove 35 in its outer rounded side, and a bolt extending through portions of said outer wall tangentially with respect to said removable bearing and engaged in the groove of the latter to hold said bearing removably engaged in said opening.

3. In a power applying unit of the character described, a support having spaced front and rear walls, a drum shaft extending between and removably mounted in said walls, a drum and gear unit rotatably mounted on said shaft between said walls and releasable for removal from between said walls by removal of said shaft, a bearing carried by said rear wall and a bearing accommodating opening in said front wall, a one-piece bushing-like bearing removably engaged in said opening, a power shaft extending between said walls and journaled in said bearings, a pinion rigid with said power shaft and in mesh with said gear, said removable bearing having a peripheral groove, a bolt extending through portions of said front wall and engaged in said groove and serving to removably retain said removable bearing in said opening, said pinion being of larger diameter than said shaft, said opening being of a diameter to permit removal of said power shaft and pinion therethrough as a unit upon removal of said removable bearing, and cooperating means between on said gear and pinion holding said pinion and power shaft against removal as long as said drum and gear unit is operatively disposed between said walls with said gear in mesh with said pinion, said cooperating means being released by removal of said drum and gear unit to permit free removal of said power shaft and pinion unit upon removal of said removable bearing.

AUGUSTUS F. KLASING.
